ROTOR VENTILATION FOR
TURBOGENERATORSMalcolm D. Ross, Pittsburgh, Pa., assignor to
Westinghouse Electric Corporation, East Pitts-
burgh, Pa., a corporation of Pennsylvania

Application May 13, 1947, Serial No. 747,683

2 Claims. (Cl. 171—252)

1

My invention relates to turbogenerators, which are synchronous dynamo-electric machines adapted to be direct-connected to a steam turbine. Such generators have a very special design, which has been successfully developed after years of experience, the principal difficulty being to design the rotor-member to be able to withstand the extremely large stresses due to centrifugal force. The design of turbogenerators is in a large measure the design of its rotor. The diameter of the rotor is strictly limited by the peripheral speed, resulting in a machine-design of great axial length. The rotor-member has become standardized as a cylindrical core having axially extending peripheral slots carrying concentric-coil field-windings.

The object of my present invention is to provide such a turborotor with reamed-out radial outlet-holes in the retaining-rings, and preferably also in the rotor teeth, so that these outlet-holes are shaped in the form of diffusers. By this simple method, at a very trifling cost, I have been able to achieve an increase of at least three or four percent in the rotor-output of turbogenerators. This increase is due, I believe, to a reduction in the gas-pressure which is lost in producing high-velocity jets leaving these radial outlet-holes. The importance of recovering as much as possible of the energy in these high-velocity jets—once said problem is given serious consideration—will be appreciated when it is realized that a large part of the total available gas-pressure, for ventilating a turbogenerator rotor, is dissipated in producing these high-velocity jets, considering also that almost one-half of the total losses in a turbogenerator is the friction-loss, which is primarily the power required to ventilate the stator and rotor members of the machine. And yet, notwithstanding the almost negligible cost of reaming these radial outlet-holes in the rotor, turborotors have been standardized, for many years, with radial outlet-holes of uniform cross-section.

My invention consists in the structures, combinations, parts, design-methods, and systems, hereinafter described and claimed, and illustrated in the accompanying drawing, wherein:

Figure 1 is a somewhat diagrammatic, simplified, longitudinal sectional view of a part of a turbogenerator;

Fig. 2 is a cut-away diagrammatic perspective view of one end of the rotor; and

Figs. 3 and 4 are detailed sections showing the radial outlet-holes through a retaining-ring and through a rotor-tooth, respectively.

2

Figure 1 shows a turbo-generator having a stator-member 1, carrying a 3-phase primary winding 2, and a rotor-member 3 which embodies the novel ventilation-system of my present invention. The rotor-member comprises a rotor-core 4 which is integral with a shaft 5. As shown in Fig. 2, the rotor-core is provided with substantially axially extending slots 6 which carry the coil-sides 7 of a concentric field-winding. The field-winding has end-turns 9 which extend beyond the ends of the rotor-core 4, and which are restrained against centrifugal force by a retaining-ring 11, which surrounds the end-turns 9 at each end of the rotor. The outer end of each retaining-ring 11 is closed by an end-plate 12 which has a centrally disposed gas inlet opening 13, and sometimes also additional openings 14, for the admission of a gaseous ventilating-medium, which is usually hydrogen in modern machines, although air has sometimes been used.

As pointed out in the Fechheimer Patent No. 1,927,890, filed December 19, 1930, the ventilation of these end-turns 9 has long been a problem, which Fechheimer solved by the use of high velocities of the gaseous medium, through narrow spaces between the end-turns 9, this gaseous medium being thrown radially outwardly by centrifugal force, and escaping through a plurality of substantially radial ventilating-openings or outlet-holes 15, which are provided in each diffuser plate 11. Prior to my present invention, these outlet-holes 15 have been of uniform cross-section, and they have resulted in the formation of high-velocity jets of ventilating-gas, discharging from these holes. According to my present invention, I ream out these ventilating-holes 15 in the form of a diffuser, with an angle of about 11° (more or less) between the opposite side walls of the ventilating-holes 15, so that these ventilating-holes are of widening diameters as the gaseous ventilating-medium passes out through said ventilating-holes in the retaining-rings.

In the design of most turbogenerator rotors, it is desirable, in addition to the end-turn ventilation, to ventilate the coil-sides 7 which lie in the slots 6 of the rotor-core 4. A desirable way to accomplish this coil-side ventilation is shown in the Kilgore Patent No. 2,094,358, filed May 29, 1936, according to which the rotor-slots 6 are provided with enlargements 16, which are shown, in my drawing, as being underneath the winding-receiving portion of the rotor-slots. Thus, the slot-enlargements 16 constitute axial ventilating-passages for receiving the gaseous ventilating me-

dium, for coiling the coil-sides 1 of the rotor-winding. Near the axial center-line of the machine, as covered by the Kilgore patent, substantially radial outlet-vents or holes 17 are provided, preferably in the form of slightly inclined tooth-openings or holes which are drilled through the rotor-teeth 18, between the rotor-slots 6. These approximately radial tooth-holes 18 provide a communication between the rotor-periphery and the axial ventilating-passages 16 of the rotor, so as to provide outlet-ducts for the rotor-ventilation.

In accordance with my present invention, it is preferable also to ream out the outer portions of these outlet-holes in the rotor-teeth, as shown at 19, so that these tooth-openings will be of widening diameters as the ventilating-gas passes out therethrough to the rotor-periphery. Although the advantages which have been discovered to result from the reaming of these tooth-openings are not as great as the advantages which have been discovered to flow from the reaming of the outlet-holes in the retaining-rings, the cost of the reaming is so slight that it is usually desirable to ream both sets of outlet-holes, as described.

I claim as my invention:

1. A turbogenerator having a rotor comprising a slotted rotor-core having rotor-teeth between the rotor-slots, a concentric field-winding having coil-sides in the rotor-slots and having end-turns extending beyond each end of the rotor-core, a

5 retaining-ring surrounding the end-turns at each end of the rotor, and an end-plate at the end of each retaining-ring, each end-plate having a centrally disposed gas-inlet opening for the admission of a gaseous ventilating-medium, and each retaining-ring having a plurality of approximately radial diffuser-type ventilating-openings therethrough, being of widening diameters as the gaseous ventilating-medium passes out through said ventilating-openings in the retaining-rings.

10 2. The invention as defined in claim 1, characterized by said rotor-slots having enlargements constituting axial ventilating-passages, and said rotor-teeth having approximately radial, diffuser-type tooth-openings extending from the rotor-periphery into communication with said axial ventilating-passages, said tooth-openings being of widening diameters as the gaseous ventilating-medium passes out therethrough to the rotor-periphery.
